(57) **CLAIM**

The ornamental design for a multitool, as shown.

DESCRIPTION

FIG. 1 is a front right perspective view of a multitool.

FIG. 2 is a front left perspective view thereof.

FIG. 3 is a top left side perspective view thereof.

FIG. 4 is a top right-side perspective view thereof.

FIG. 5 is a bottom left side perspective view thereof.

FIG. 6 is a bottom right-side perspective view thereof.

FIG. 7 is a front right perspective view of a second embodiment of a multitool.

FIG. 8 is a front left perspective view thereof.

FIG. 9 is a top left side perspective view thereof.

FIG. 10 is a top right-side perspective view thereof.

FIG. 11 is a bottom left side perspective view thereof; and, FIG. 12 is a bottom right-side perspective view thereof.
